UNITED STATES PATENT OFFICE.

JOSEF HIRSCHMANN, OF ESPYVILLE, PENNSYLVANIA.

ROLLING MILL.

Application filed October 22, 1920. Serial No. 418,700.

To all whom it may concern:

Be it known that I, JOSEF HIRSCHMANN, a citizen of the United States and resident of Espyville, in the county of Crawford and State of Pennsylvania, have invented a new and useful Improvement in Rolling Mills; and I do hereby declare the following to be a full, clear, and exact description thereof.

My invention relates to rolling mills and is particularly adapted for the rolling of sheet-metal although I do not wish to limit it to this particular product.

In mills of this character as heretofore constructed where a two high mill with a balanced top roll is used, it was generally necessary to use a stand of pinions to transmit the power to the top roll. These pinions were constructed with teeth strong enough to stand the actual rolling of the metal as the top roll, as well as the bottom roll, was positively driven, and consequently these pinions had to be very large and massive and mounted in correspondingly large massive housings, thereby greatly increasing the cost of mills of this character, not to mention the great amount of power required to drive same.

The object of my invention is to dispense with these expensive pinions and pinion-housings, and in order to accomplish this object I provide a mechanism for driving the upper roll of the mill independently of the lower roll which is broadly the gist of my invention.

In the accompanying drawing Fig. 1 is a longitudinal vertical elevation of a mill showing my invention applied thereto, the housing of the mill proper being partly shown in section; and Fig. 2 is a section on the line 2—2, Fig. 1.

In the drawing the numeral 2 designates a suitable bed-plate or shoe provided with the spring bearings 3 which support the spindle 4 for driving the lower rolls. In the drawing I have shown one pair of rolls in full and another pair partly broken away, the spindle 4 forming a driving connection from the bottom roll of one pair to the bottom roll of the next pair.

The spindle 4 is connected up to the lower rolls 6 in the ordinary manner by the usual coupling boxes 5.

The roll-housings 7 are of the ordinary construction in which the rolls are journaled and, as in the case illustrated where a balanced mill is employed, the upper roll 8 is

supported in a bolster 9 supported on bars 10 which are connected with a system of levers 11 and 12 and balance weights 13 suspended beneath the bed-plate, and which balance weights are sufficient to lift the top roll as the feed-screws 14 are turned back so as to keep the roll constantly in contact with its top bearing.

Bolted to the shoe 2 are the castings 15 which form a support for the bed-plate 16 which is bolted thereto and which forms a support for the mechanism for driving the top roll 8.

A suitable electric motor 17 of requisite power is bolted to the bed-plate 16, and the motor shaft 18 is connected up by the suitable semi-universal coupling 19 to the gear-transformer 20 which may be of any suitable construction to reduce the high speed of the motor and provide power enough to keep the upper roll at the same speed as the lower roll when no metal is passing through the mill. As any suitable form of gear-transformer may be employed it has not been deemed necessary to illustrate the same in detail.

A spindle 21 connects with the gear-transformer through a friction coupling 21^a to the top roll 8 for driving same, and said spindle has at its outer end a coupling 22 which fits over the wabbler-end of the top roll, there being sufficient play between said coupling and said end to allow for considerable play to prevent the shock created by the metal leaving the roll from being transmitted to the gears in the gear-transformer. In this manner a sudden stress on the gears in the gear-transformer is practically eliminated.

As the upper roll is thus operated by independent power from that which operates the lower roll it is not necessary to have the upper roll rotating when the mill is not in use which creates a great saving in power and at the same time a saving in the wear of the parts.

When my improved mill is in operation in the rolling of metal, the lower roll is driven in the ordinary manner from the mill engine through the spindle 4, and the upper roll is driven independently by power transmitted from the motor 17 through the gear-transformer 20. As above stated, the motor only needs to supply power enough to keep the upper roll at the same speed as the lower roll when no metal is passing through the

rolls, but just as soon as the metal enters the rolls the upper roll is driven by friction of the metal passing between it and the bottom roll.

5 By my invention I am able to dispense with the massive pinions and pinion housings ordinarily employed for driving the top roll positively from the bottom roll together with the expense of such installation 10 and furthermore, doing away with the necessity of having the upper roll in operation when the roughing stand is not in use. Heretofore, in a train of rolls all the top 15 rolls of the different trains were continuously driven due to their being connected up by the pinions, but by my invention the upper roll of any stand of a train may be stopped when the stand is not in use, thereby creating a great saving in power as well 20 as in wear and tear.

What I claim is:

1. In a bar rolling mill, the combination 25 of cooperating upper and lower rolls, power drive means connected to the lower roll independently of the upper roll for operating the mill, and idler means connected independently to the upper roll, for lightly turn-

ing the same to initiate feed of the plate and permit subsequent driving of the upper roll from the lower roll through friction of the 30 plate.

2. In a bar rolling mill, the combination of cooperating lower and upper rolls mounted out of contact, means for exerting great pressure on the rolls, power means to rotate the lower roll to drive the work through the mill, a light motor independent of the power means and the lower roll for driving the upper roll, a reduction gear between the light motor and the upper roll, a loose coupling in the upper roll drive adjacent the upper roll, and a friction coupling located between the loose coupling and the reduction gear.

3. The combination with a two-high sheet 45 rolling mill stand having a drive for its bottom roll, of a separate motor drive connection for the top roll, said connection comprising a motor, a reducing gear, a slip device, and a universally jointed shaft coupled to said roll, substantially as described.

In testimony whereof I, the said JOSEF HIRSCHMANN, have hereunto set my hand.

JOSEF HIRSCHMANN.
